United States Patent Office.

FRANCIS M. BACHMAN AND SAMUEL RICKER, OF FREDERICKSBURG, PENNSYLVANIA.

Letters Patent No. 100,489, dated March 8, 1870.

IMPROVEMENT IN FAUCETS.

The Schedule referred to in these Letters Patent and making part of the same.

To all whom it may concern:

Be it known that we, FRANCIS M. BACHMAN and SAMUEL RICKER, of Fredericksburg, in the county of Lebanon, and State of Pennsylvania, have invented a new and useful Improvement in Faucets; and we do hereby declare that the following is a full, clear, and exact description thereof, which will enable others skilled in the art to make and use the same, reference being had to the accompanying drawings forming part of this specification, in which—

Figure 1 is a longitudinal section of our improved faucet.

Figure 2 is a cross-section of the screw-plate or cap.

Similar letters of reference indicate corresponding parts.

Our invention has for its object to furnish an improved faucet, which shall be so constructed that it will entirely prevent leakage through it, and will enable the cask to be easily and quickly tapped without the loss of any of the liquid, however great may be its pressure; and

It consists in the construction and combination of various parts of the faucet, as hereinafter more fully described.

The inner or stop-faucet is made in two parts, the tube or case A and the plug or valve B.

The plug or valve B is fitted or ground into the interior of the tube A, is made hollow, and has one or more holes formed through the side of the inner end, corresponding in number, size, and position with a similar set of holes formed through the upper side of the inner part of the tube A.

The plug or valve B is secured in place in the tube A by a nut, C, screwed upon its inner end, a washer, D, being interposed between the said nut and the end of the tube A, as shown in fig. 1.

The outer part of the tube A is enlarged, to leave a space between it and the outer part of the hollow plug or valve B, to receive the tubular nut, by means of which the tapping-faucet is secured to the stop-faucet.

The enlarged part of the tube A has a screw-thread formed upon its outer surface, to enable it to be screwed into the cask, and another screw-thread cut upon its inner surface, to receive the screw-thread of the plate or cap E, to close the outer end of the stop-faucet A B when the tapping-faucet is detached.

The outer edge of the flange or face-plate a' of the

tube A is made polygonal in form, for convenience in applying a wrench to screw the said stop-faucet A B into the cask.

F is the tapping-faucet, which is similar to an ordinary faucet, except that it has a tubular nut, H, placed upon it, and a collar, G, formed upon or attached to it, against which a shoulder, formed upon the interior of the tubular nut H, rests, to securely hold the tapping-faucet in place in the stop-faucet.

The tubular nut H has a screw-thread, formed upon the inner surface of its forward part, to screw into a screw-thread formed upon the outer surface of the outer end of the hollow plug B.

The inner end of the tapping-faucet F fits into the outer end of the hollow plug B.

One side of the forward end of the tapping-faucet F is flattened to fit upon a flattened part of the inner surface of the hollow plug B, said flattened parts being so arranged that the holes in the forward part of the hollow plug B may correspond with the holes in the tube A, when the faucet F is in proper position for drawing the liquid; that is to say, when it is right side up.

The stop-faucet A B is designed to be permanently attached to the cask.

When the cask is to be tapped the screw-plate or cap E is screwed off, the tapping-faucet is placed in the hollow plug B bottom side up, and is secured in place by the tubular nut H. The tapping-faucet F is then turned right side up, which opens the communication between the interior of the cask and the interior of the faucet, so that the liquid may be drawn from the cask by operating the plug I of the faucet F in the ordinary manner.

The tapping-faucet may at any time be removed by reversing the above-described operation.

Having thus described our invention,

We claim as new, and desire to secure by Letters Patent—

The combination of the stop-faucet A B and tapping-faucet F G H with each other, said parts being constructed and operating substantially as herein shown and described and for the purpose set forth.

FRANCIS M. BACHMAN.
SAMUEL RICKER.
